FLUID INJECTOR PUMP HOUSING

Volney M. Jemison and Don H. Young, both of
1423 S. 28th St., Phoenix, Ariz.

Filed Dec. 20, 1961, Ser. No. 67,992

Term of patent 14 years

(Cl. D65—1)

FIG. 1 is a perspective view of the front and one side of a fluid injector pump housing showing our new design;

FIG. 2 is an elevational view of the side opposite that shown in FIG. 1, and

FIGS. 3 and 4 are front and rear elevations respectively thereof.

We claim:

The ornamental design for a fluid injector pump housing, as shown.
